UNITED STATES PATENT OFFICE.

RALEIGH J. FREDERICKSON, OF MARION, SOUTH DAKOTA.

PRINTING, DEVELOPING, AND FIXING APPARATUS.

Application filed May 11, 1920. Serial No. 380,471.

To all whom it may concern:

Be it known that I, RALEIGH J. FREDERICKSON, a citizen of the United States, residing at Marion, in the county of Turner and State of South Dakota, have invented certain new and useful Improvements in Printing, Developing, and Fixing Apparatus, of which the following is a specification.

The present invention relates to improvements in machines for printing, developing and fixing photographs on paper having a sensitized surface, and is particularly designed for use where the printing is to be done on paper in cut-sheet or card form, suitable mechanism being provided for rapidly and efficiently handling the sheets or cards within the machine without the danger of accidental exposure while passing through the several stages necessary to the production of a finished print.

The machine is further characterized by the fact that the sensitized sheets or cards for use with the machine are carried in a package or cartridge which can readily be attached to or detached from the machine proper without danger of accidentally exposing the sheets. It is thus possible to make prints from the desired negative on any grade or kind of paper regardless of the number of sheets already used from a cartridge by merely removing the cartridge in use and substituting another containing sheets of the proper grade and surface. A further advantage of the present machine over those using a roll of sensitized paper, is that the sheets or cards lie flat and do not tend to curl.

While possessing all the advantages of prior types of printing and developing machines which are quite cumbersome and require considerable space in which to be set up, the present device may readily be folded into compact form for transportation and quickly set up for use whenever desired. It is therefore especially adapted to the use of travelers and campers, and others desiring to do their own printing and developing.

Other and further advantages of the invention will appear upon consideration of the following description taken in conjunction with the accompanying drawings, in which,

Figure 1 represents a longitudinal section of the machine with a cartridge of the sen-

sitized sheets in place, the pressure plate behind the exposure glass being shown in position for receiving one of the sensitized sheets dropping from the cartridge;

Fig. 2, a similar view with the sensitized sheet pressed into place against the exposure glass ready for printing, the pressure plate being shown, in dotted lines, in retracted position whereby the sensitized sheet after being exposed, is permitted to drop into the developing tray below;

Fig. 3, a side elevation of the machine;

Fig. 4, a front elevation of the same with the exposure door open;

Fig. 5, a section taken on line 5—5 of Fig. 1;

Fig. 6, a section taken on line 6—6 of Fig. 2;

Fig. 7, a perspective of the machine in folded or collapsed form with the cartridge of sensitized sheets removed;

Fig. 8, a perspective of the top of the machine with the cartridge attached, a portion of the latter being broken away to show more clearly the arrangement of the parts;

Fig. 9, a transverse section of the top of the machine and the attached cartridge, as shown in Fig. 8;

Fig. 10, a perspective of the cartridge with a portion of the cover broken away to show more clearly the arrangement of the sheets therein, and

Fig. 11, a perspective of the package containing the sensitized cut sheets in the container in which it is placed when not in use in the machine.

The machine in general consists of a main compartment in which the sensitized sheets are printed and developed, a cartridge or package containing a supply of sensitized sheets to be fed to the printing and developing compartment, and a fixing compartment into which the developed sheets are passed and from which they may be removed when finished.

Referring to the drawings, 1 and 2 represent the members, preferably of wood, forming the front and back respectively of the casing forming the printing and developing compartment. Member 2 is pivotally connected at its top by suitable means 3 to side extensions 4 and 5 of front member 1, and at its lower edge to the casing which forms the fixing compartment 6 by means of hinges 7. Suitable light-proof flexible

material 8, extending between members 1 and 2, forms the sides of the printing and developing compartment, so that the parts may be folded into collapsed form when desired, as shown in Fig. 7. A collapsible strut 9 on either side of the printing and developing compartment, and extending between and pivotally connected at its ends to members 1 and 2, serves to maintain the lower ends of these members in proper position when the machine is set up for use.

An opening 10 is provided in front member 1 of the printing and developing compartment through which light is admitted for printing the sensitized sheets. Removably mounted in opening 10 is a glass plate 11, secured on one side by clips 12 and on the other side by catch 13 whereby plate 11 may be removed when desired. The negative 14, which is shown in roll form merely by way of example, is carried on spindles 15 and 16 removably mounted in suitable brackets 17 and 18, located respectively above and below opening 10. Negative 14 extends over opening 10 and behind glass 11, suitable spaces being left between the ends of the glass and the top and bottom of opening 10 for this purpose. When it is desired to use glass negatives instead of roll negatives, glass 11 may be removed and the desired negative readily substituted, if of proper size. If cut-film negatives, or glass negatives smaller than opening 10, are used, a suitable septum, secured in place by clips 12 and clamp 13, may be used to hold the negative in proper position. A door 19 hinged to the face of member 1 serves when closed to exclude light from the printing and developing compartment through opening 10 when desired.

Removably attached to the top of the printing and developing compartment is the cartridge or package containing the supply of sensitized sheets. This cartridge, which is preferably made of cardboard, consists essentially of a box member 20 and a top 21, suitably hinged together at 22 and containing a series of sensitized sheets 23. When not in use, the cartridge proper is intended to be placed in a suitable container 24, thus insuring against accidental opening of the cartridge and exposure of the sensitized sheets.

Provided at the upper edges of front and back members, 1 and 2, of the printing and developing compartment, are hinged members 25, the free ends of which are adapted to slip under clips 26 provided on the outer faces of members 20 and 21 of the cartridge, whereby members 20 and 21 are held in proper position to permit the feeding of sheets 23 to the printing mechanism. A light-proof apron 27 secured at its lower edge to the printing and developing compartment and provided at its upper edge

with a resilient cord 28 to hold the apron in place about the cartridge, serves to exclude light at this point.

The sensitized sheets 23 are mounted in box member 20 of the cartridge, which is open at the bottom, each of said sheets being secured at its upper edge to the top of member 20 by means of a frangible strip 29. A series of cords 30, one for each of the sheets 23, extend from the lower part of member 20, where they are secured at 31, diagonally across the faces of sheets 23, around strips 29 and out of the top of the cartridge at an opening 32 in member 20. It will thus be seen that upon pulling one of the cords 30, the corresponding strip 29 will be severed and the sheet 23 which it supports released, whereupon the sheet will fall through the lower end of box member 20 into the printing compartment, as shown in Fig. 1. In order to prevent the possible entrance of light through opening 32, a felt or other pad 33, held in place by spring 34, is provided, which however in no way interferes with the functioning of cords 30. Cords 30 further serve to prevent all but the sheet about to be released, i. e., the sheet towards the front of the machine, from swinging outward and thus interfering with the proper releasing of that sheet. A strip 35 secured to the sides of member 20 prevents the sheet being released from swinging out and catching on the lower edge of cover 21. A suitable guide 36, secured to the rear face of member 1 above opening 10 and directly beneath the opening in the top of the printing and developing compartment through which the sensitized sheets fall, serves to direct each sheet 23, as it is released, to the printing mechanism.

Means are provided within the printing and developing compartment at the rear of exposure glass 11 for receiving sheets 23 as they are released and pressing them firmly against negative 14 and exposure glass 11 during the printing operation. Journaled in side members 4 and 5 is a shaft 37 carrying rigidly secured thereto a pair of downwardly extending arms 38. Pressure plate 39, which receives sheets 23 as they are released from the cartridge, is provided at its lower corners with brackets 40 having pins 41 engaging slots 42 in the lower ends of arms 38, thus supporting the lower end of the pressure plate. Rotatably mounted on shaft 37 is a yoke 43 carrying a pair of downwardly projecting arms 44 pivotally connected at their lower ends to brackets 45 secured at the upper corners of plate 39, whereby the upper end of plate 39 is supported. A crank 46 on the end of shaft 37 and a similar crank 47 on the end of a tubular extension 48 on yoke 43 provide means outside the printing and developing compartment for swinging pressure plate 39 to

any desired position. A catch 49 holds crank 47 during the printing operation.

Secured to the lower edge of plate 39 by means of springs 50 is a ledge 51 adapted to catch sheets 23 when released from the cartridge and hold them in place on plate 39. It will thus be seen that when plate 39 is swung into position against negative 14, springs 50 will permit ledge 51 to swing back so as not to interfere with the proper functioning of the pressure plate.

The apparatus for developing the exposed sheets is located just beneath the printing mechanism. A tray 52 adapted to contain a suitable developing fluid is located in the lower part of the printing and developing compartment on the support upon which the machine rests. Overlying one end of tray 52 is a roller 53 having its shaft 54 journalled in a pair of blocks 55 pivotally secured to hinges 7. A crank 56 is provided on the end of shaft 54 for rotating roller 53. A pair of brackets 57 secured to the inner face of front member 1 serves to support another and smaller roller 58 at the other end and near the bottom of tray 52. Passing around rollers 53 and 58 is a series of resilient endless bands 59. Loosely mounted on shaft 54 of roller 53, is a yoke 60 provided with an extension 61 and a series of prongs 62 overlying endless bands 59. A crank 63 is provided on the end of a tubular extension 64 on yoke 60 whereby the yoke and its prongs 62 may be rotated about shaft 54.

Thus, it will be seen that, when an exposed sheet has fallen on endless bands 59, the bands, yoke 60 and its prongs 62 being in the position shown in Fig. 1, rotation of crank 63 in a counter-clockwise direction will cause yoke 60 through extension 61 to depress the resilient bands 59 well beneath the developing fluid in tray 52, while prongs 62 descending with yoke 60 serve to submerge the sheet in the fluid, as shown in Fig. 2. Yoke 60 with prongs 62 are then returned to their original position by means of crank 63, thus allowing bands 59 to again assume the position shown in Fig. 1, and thereby lift the print out of the developing fluid. A transparent plate 65 of suitable material is provided in back member 2 of the printing and developing compartment whereby the operations incident to printing and developing may be observed without permitting entrance of actinic light.

Located in the bottom of the fixing compartment 6 on the support on which the machine rests, is another tray 66 adapted to contain a suitable fixing fluid. An opening 67 in the end of fixing compartment 6 permits passage of the prints from the developing to the fixing apparatus, as shown in Fig. 1. Handle 56 being turned clockwise, the print resting on endless bands 59 will be

carried over roller 53 through opening 67 into the fixing tray 66. A door 68 having a handle 69 is provided in the top of the fixing compartment 6 whereby prints may be removed from tray 66. In order to prevent communication between the printing and developing chamber and the fixing chamber when door 68 of the latter is open, a door 70 is provided for opening 67 which closes said opening when door 68 is raised, as in Fig. 2, and is automatically raised to permit the passage of developed prints to the fixing compartment when door 68 is closed, as in Fig. 1. This is accomplished by means of a lever 71 loosely mounted on a shaft 72 journalled in the sides of compartment 6, said lever having a weighted extension 73 whereby the opposite end of the lever is kept constantly in engagement with the under side of door 68. A projection 74 on door 70 is adapted to be engaged by the extension 73 of lever 71 to raise door 70 when door 68 is closed, as shown in Fig. 1, and to be disengaged from projection 74 to allow door 70 to close when door 68 is open, as shown in Fig. 2.

The desired negative having been placed before opening 10 in member 1, and a cartridge containing sensitized sheets of the proper grade and so forth, having been attached, the operations incident to the making of each finished print are substantially as follows:—

Pressure plate 39 is swung into the position shown in Fig. 1 by the proper manipulation of cranks 46 and 47, and door 19 closed in order to exclude light from the developing and printing compartment. The first cord 30 towards the front of the machine is then pulled, thereby severing the corresponding strip 29 and releasing the sheet 23 supported by said strip; whereupon, the released sheet 23 slides into the printing and developing compartment, guided by strip 35 and guide 36, on to pressure plate 39, the lower edge of sheet 23 resting on ledge 51. Cranks 46 and 47 are then manipulated again to bring pressure plate 39 into the position shown in Fig. 2, with sheet 23 firmly clamped against the rear face of negative 14. Door 19 is then held open until sheet 23 has been exposed to the light for the desired period, whereupon the door is closed.

The exposed sheet 23 being ready for developing, cranks 46 and 47 are manipulated to swing pressure plate 39 into the dotted line position shown in Fig. 2. Sheet 23 will then slide from plate 39 over ledge 51 on to endless bands 59. Crank 63 is then rotated to depress bands 59 through yoke 60 and extension 61, while prongs 62 descend upon print 23 and force it beneath the surface of the developing fluid in tray 52, as shown in Fig. 2. At the end of the desired period,

crank 63 is operated to return the parts to their original positions, whereupon crank 56 is rotated to feed the developed print forward through opening 67, door 70 being 5 open as door 68 is closed, into fixing tray 66 containing a suitable fixing fluid. After the fixing period door 68 is raised, whereupon door 70 is automatically closed as explained, and the finished print removed and 10 dried in any suitable manner.

While the foregoing description and the drawings set forth a practical embodiment of the invention, it is not intended that the invention shall be confined to the exact 15 means shown and described except as limited by the appended claims.

What I claim is:—

1. In a machine of the character described, the combination of a collapsible casing having an opening in the upper portion thereof for the passage of sensitized sheets; printing mechanism located in the front part of said casing; a removable cartridge of sensitized sheets attached to said casing 20 in a partially open position over the opening in the casing; means for feeding the sensitized sheets one at a time through said opening in the casing to the printing mechanism; developing means located in the lower 25 part of said casing; a second casing to which said first mentioned casing is pivotally connected at its rear edge; and fixing means located in said second-mentioned casing, said first-mentioned casing being adapted to 30 fold against the upper face of said second-mentioned casing when in collapsed form.

2. In a machine of the character described, the combination of, a casing having an opening in the upper portion thereof for the passage of sensitized sheets; printing mechanism located in the front part of said casing; a removable cartridge of sensitized sheets attached to said casing in a partially open position over said opening in the casing; means for feeding the sensitized sheets 40 one at a time through said opening in the casing to the printing mechanism; a tray in the lower part of said casing adapted to contain a developing fluid; a roller supported above the bottom of said tray at the 45

forward end thereof; a second roller extending across said tray at its opposite end; endless resilient bands carried by said rollers; means for feeding the exposed sheets one at a time from the printing mechanism upon 55 said endless bands; means for depressing said bands beneath the surface of the fluid in said developing tray; means for submerging the sheets one at a time in the developing fluid; and a crank for rotating 60 said last mentioned roller.

3. A device of the character described, comprising in combination, a collapsible casing; printing mechanism located in said casing at the forward end thereof; developing mechanism located in the lower part 65 of said casing; a second casing attached to the first mentioned casing; and fixing means located in said second casing, said casing containing the printing and developing 70 mechanism being adapted to fold against the casing containing the fixing mechanism when in collapsed form.

4. A portable printing, developing and fixing apparatus, comprising, in combination, 75 a collapsible casing; printing mechanism located in the forward part of said casing; developing mechanism located in the lower part of said casing; a second rigid casing to which said first-mentioned casing 80 is hinged; and fixing means located in said second-mentioned casing, said first-mentioned casing folding against the upper face of the second-mentioned casing when in collapsed form.

5. In a machine of the character described, the combination of a casing having an opening in the upper portion thereof for the passage of sensitized sheets; printing mechanism located in said casing; developing mechanism located in said casing; a removable cartridge of sensitized sheets attached to said casing in a partially open position over said opening in the casing; and means for conducting said sheets one 90 at a time to said printing mechanism and thence to said developing mechanism.

In testimony whereof I have signed my name to this specification.

RALEIGH J. FREDERICKSON.
